CLAIM

The ornamental design for the kayak-paddle board rack, as shown and described.

DESCRIPTION

FIG. 1 is a perspective view of the kayak-paddle board rack.

FIG. 2 is a front view of the design of FIG. 1.

FIG. 3 is a back view of the design of FIG. 1.

FIG. 4 is a left side view of the design of FIG. 1.

FIG. 5 is a right side view of the design of FIG. 1.

FIG. 6 is a top plan view of the design of FIG. 1; and,

FIG. 7 is a bottom plan view of the design of FIG. 1.

The broken lines in the drawings illustrate environmental subject matter only and form no part of the claimed design.
